UNITED STATES PATENT OFFICE.

CHARLES JOSEPH STIMPSON, OF BRONXVILLE, NEW YORK.

SASH-CORD FASTENER.

Application filed June 2, 1927. Serial No. 195,904.

My present invention refers to certain new and useful improvements in sash cord fasteners. The primary object of the invention is to enable the cords or hanging members to be attached to window sash frames much more readily than has hitherto been possible, and especially to enable said cords to be replaced or readjusted with great facility and accuracy, without any necessity for knotting the end of the cord, and without removing the sash from the frame in repairing or reattaching the cord, a process which is always attended with great discomfort to the occupants of a room, especially in cold weather; and also the first hanging of the sash is rendered easier and quicker.

The invention, with these desirable objects and many others in view, may be said to consist essentially in a small metallic plate to which the end of the cord is removably attached, which plate is quickly and easily insertable into or removable from a small pocket on the inner face of the window sash without removing the sash from its frame and thus exposing the interior of a room to chilling drafts or other unfavorable influences.

And the invention may also be said to consist essentially in the construction, combination and arrangement of parts, substantially as will be hereinafter described and claimed.

In the annexed drawing illustrating my invention:

Figure 1 is an inner front face view of one of the stiles of a window sash, with its supporting cord, and my improved fastener for the cord applied thereto, certain parts being sectioned to bring out the detail construction and arrangement more clearly.

Figure 2 is a left hand outer edge of the same sash stile.

Figure 3 is a vertical longitudinal section of the same stile on the line 3, 3, of Figure 1, and shows the cord fastening device in edge view in its pocket.

Figure 4 is a cross section on the line 4, 4, of Figure 1.

Figure 5 is a perspective view in detail of the two principal pieces of the fastening device.

Like characters of reference denote like parts throughout all the different figures of the drawing.

A denotes one of the vertical stiles of a window sash frame, say for example the

left hand stile. The outer edge 2 of this stile, which is next to the window frame when the sash is in position, is provided with the customary groove 5 adapted to accommodate the sash cord 6, the top end of which runs over a pulley in the window frame and carries the sash weight, (not shown) while the lower end runs for a suitable distance from the top of the sash, say a few inches down through the groove 5, until it reaches a horizontal connecting or deflecting groove or passage 7 which communicates with a pocket or recess 8 in the stile A, which pocket 8 has an opening on the inner face 1 of stile A and is fitted with a pivoted or hinged cover 9, said pocket 8 being adapted to receive and hold the fastening device which thus fastens the cord 6 to the sash. The inner edge of stile A is formed with a bead α opposite to groove 5, which bead acts as the usual shoulder against which the pane of glass 3 is secured by brads and putty 4 or by any other means.

The cord fastener consists of a small rectangular metallic plate 10, having one or more openings or perforations 11, and at one end a right-angled flange or lug 12. Plate 10 is adapted to be seated in the bottom of recess 8, wherein it lies flat or more or less inclined, one end being lifted away from the bottom of the recess 8 by the lug 12, or if the cord 6 is larger than the width of lug 12, the cord itself will lift the end of plate 10 and the lug 12 away from the bottom of recess 8, and it is so shown in Figure 3; but in many cases the cord will be smaller than the width of lug 12 and will pass through passage 7 from groove 5 and lie under the plate 10, the cord being turned at an angle to permit this. The cord will also be against the inner face of lug 12, whose edge as stated may or may not touch the bottom of recess 8, depending on the thickness of the cord.

The cord also in its attachment to plate 10, not only turns at an angle to pass under it, but it is also passed through the round hole or opening 11 in plate 10, and then allowed to lie close against plate 10. The cord is clamped tightly in this position against plate 10 by means of a clamping plate 14, having at its ends the angular or right-angled flanges 15, which are preferably toothed or serrated at 16. When the clamp 14 is in position binding over cord 6 as shown in Figures 1 and 3 it will be secured

to plate 10 by screws 17 entering screw holes in clamp 14 and coincident screw holes in plate 10, see Figure 5, and thus the clamp 14 clamps very tightly against cord 6, and 5 its toothed flanges bite into the cord 6, so that a gripping of the cord takes place which cannot be released no matter how hard a pull is applied to cord 6, and it is therefore impossible to detach the cord from the sash 10 by hard and prolonged usage, and it will do its work effectually until worn out or broken and rendered useless, when the end can easily be taken out by removing clamp 14, and then inserting the end of a new cord, 15 and re-securing the clamp over it.

It will be seen that in inserting this cord, either a fresh one or a repaired one, it can be pushed down through the groove 5 from the top of the sash, without taking the sash 20 out of the window, and when the lower stiff end of cord 6 strikes the cross groove 7 it will be deflected sidewise into the pocket 8, where it can readily be taken hold of and the fastener device clamped thereon, so that 25 when the cord is pulled back from above, the fastener device will lodge itself firmly in the pocket 8, thus connecting the cord tightly to the sash; and the repeated movements of the sash up and down in opening 30 and closing the window will only serve to more and more tightly anchor the fastener in the pocket 8. And it is to be particularly noted that access to the pocket 8 is had on the inner face 1 of sash stile A by simply 35 switching away the cover 9 that is held by screws 13, 13, or otherwise. Thus in connecting the cord to its fastener I do not disturb the sash itself. It remains as usual in its frame, and the window is kept shut. 40 The repair or readjustment is made very

quickly, and is positive and sure. The device is simple and economical and thereby many useful results are made possible.

Many changes in the details of parts and their relative sizes and positions may be 45 made without departing from the invention as covered by the ensuing claim. Obviously a single window has two sashes and hence four cords are necessary, or two for each sash; but each cord may make use of 50 my improved fasteners with equal facility. And indeed the fastener may be applied to weighted cords employed with other kinds of windows, or doors, or other similar structures without varying from the invention. 55 It is important to note that the cord is without knots or clasps for holding it, as none are needed when my improved fastener is used.

Having thus described my invention what 60 I claim as new and desire to claim, is:

In a sash cord fastener, the combination with a window sash having the stile provided with a groove receiving the cord and a pocket in communication with said groove, of a fastener adapted to be seated in said pocket and consisting in a flat plate perforated near one end through the perforation of which the cord is passed, said plate having an angular lug adjoining the perforation, 70 and a clamp for clamping the cord between itself and the plate so that the cord may be held tightly against the plate, said clamp having angular toothed flanges that engage the cord, and screws entering holes in the clamp and plate for uniting the clamp and plate tightly together.

In testimony whereof I hereunto affix my signature.

CHARLES JOSEPH STIMPSON.
